JOHN L. WAGNER, OF SYRACUSE, NEW YORK, ASSIGNOR TO THE PNEUMELECTRIC MACHINE COMPANY, OF SYRACUSE, NEW YORK, A CORPORATION OF NEW YORK.

PRESSURE-DEVELOPING PNEUMATIC TOOL.

1,093,302.

Specification of Letters Patent. Patented Apr. 14, 1914.

Application filed March 1, 1910. Serial No. 546,686.

To all whom it may concern:

Be it known that I, JOHN L. WAGNER, a citizen of the United States, and resident of Syracuse, in the county of Onondaga and 5 State of New York, have invented certain new and useful Improvements in Pressure-Developing Pneumatic Tools, of which the following is a specification.

This invention relates to tools, which develop a percussive stroke from the expanding force of air under pressure and particularly to that class of such tools in which the compression of the air is developed by the tool or machine itself through the medium 15 of a piston that reciprocates in such relation to the tool piston (preferably in the same cylinder therewith) that it not only compresses and then releases a body of air to act expansively against the tool piston, but it 20 retracts the tool piston during the compressing stroke, to a position in which it will encounter the force of the expanding body of air to the best advantage.

One object of my present invention is to 25 provide means whereby the air utilized within the machine will be conserved as much as possible and the introduction of new air with its unavoidable dust will be reduced to a minimum.

Another object is to provide means whereby a portion of the body of air compressed as stated, may be utilized for the purpose of increasing the pressure on the forward face of the tool piston above that supplied by atmosphere, so that it will respond more readily and more effectively to the suction of the compressing piston during the retracting stroke, and to these ends the invention consists of certain novel features of construction hereinafter fully described and particularly pointed out in the claims.

In the accompanying drawings: Figure 1 is a vertical longitudinal section of a machine of known type having my present improvements applied thereto, the pistons being in the positions assumed immediately after delivery of the working stroke, the tool piston being driven to the forward limit by the expanding air and the retracting 45 and compressing piston being at the comple-

tion of its compressing stroke; Fig. 2 is a view of that portion of Fig. 1 with which the invention is immediately concerned, showing the retracting and compressing piston after commencement of its rearward stroke; Fig. 3 is a view similar to Fig. 2 showing the retracting and compressing piston and the tool piston after the latter has completed its rearward stroke; and Fig. 4 is a detail view showing a modified construction of the cylinder.

Referring to Fig. 1, 1 represents a suitably housed electric motor connected through any suitable gearing 2, which translates rotary into reciprocating motion, to the rod 3 of the compressing and retracting piston 4, fitted to reciprocate in the cylinder 5, in which is also housed a tool piston 6 adapted to percussively actuate a tool as for instance through its forwardly projecting rod 7. 70 Piston 4 is constantly reciprocated in the cylinder 5 and in so acting, it expels air through a valved port 8, on its forward stroke, until it reaches its limit in close proximity to the piston 6, then on its rearward movement, it develops a partial vacuum behind the piston 6 so that the latter tends to follow it rearward under atmosphere or other pressure and at the same time the said rearward movement of the piston 4 compresses a considerable body of air behind it at the rear end of the cylinder 5, and in a reservoir 9 through port 10, until the pistons 4 and 6 approach their rearward limit of movement, when the highly compressed 80 air in rear of the piston 4 will enter through a port 11, which has then been uncovered by the piston 4 and, expanding, will drive the piston 6 forward to develop the percussive stroke, after which the piston 4 again 85 moves forward, to repeat the cycle of steps. During the forward stroke of the piston 6, air trapped in advance of it is forced through a port 12 into the reservoir 9 so as to avoid waste and reduce the introduction 90 of new air with unavoidable dust and grit. For the same consideration, it is desirable to have the port 8 also discharge into the reservoir 9. It will, of course, be understood that the pressure in advance of the piston 6 is not 100

sufficient to offer material resistance to the working stroke until piston 6 approaches its forward limit by which time the stored pressure in reservoir 9 has been so far relieved 5 through the port 11 as to permit port 12 to open and thus avoid material reduction of the efficiency of the stroke.

Some of the features of the machine as thus far described are inventions of another 10 and are, therefore, not claimed by me except in combination with features of my invention as hereinafter pointed out.

It has heretofore been proposed to open a communication with atmosphere at the 15 forward end of the cylinder 1, in front of the piston 6 so that atmospheric pressure on the front face of said piston will act to drive it rearward, when a partial vacuum is created in rear of it by retraction of piston 20 4. Under some circumstances, atmospheric pressure is not sufficient to satisfactorily retract the piston 6, as for instance, when the machine is used in a vertical position and the weight of the piston, its rod and the 25 attached tool must be overcome in addition to the friction of the moving parts. To render the retraction of the piston 6 more positive, I have provided a feed passage 13 for fluid pressure medium, which leads from 30 a port 14 near the rear end of the cylinder to a port 15 at a point beyond the extreme forward limit of the piston 6. The effect of this feed passage is to deliver to the space in front of the piston 6 some of the air pressure 35 developed during the earlier part of the rearward movement of the piston 4 and thereby exert a greater retracting pressure on said piston 6 than if merely atmospheric pressure were relied upon, as heretofore. 40 In this manner, the piston 4 is caused to exert upon the piston 6, not only the so called suction but at the same time to exert a direct pressure upon its forward face.

16 represents a replenishing valve opening 45 inward under external atmospheric pressure and replacing air, which escapes through the packings, whenever, after forward movement of the compressing piston, the pressure of the chamber or reservoir 9 50 is sufficiently reduced to enable atmosphere to overcome the spring of the valve 16.

The port 14 is located at such a point that it is not uncovered by the piston 4 in moving to its rearward limit and hence the driving 55 pressure for developing the percussion in the piston 6 cannot enter the supply passage 13 and balance the driving pressure; nor can the front air cushion be lost at end of the working stroke by escape of air 60 from in front of the tool piston after the port 12 has been covered.

According to the modification shown in Fig. 4, the reservoir 9^a is entirely distinct from the return passage 9^b with the result

that much higher initial compression will be 65 developed and delivered to the tool piston, during the covering of the by-pass 10^a and the port 11^a, will reduce the pressure in the chamber 9^a to such an extent as to draw in atmosphere on every stroke, if desired, under such conditions as may be predetermined by regulation of tension on the closing 70 spring of the valve 16.

Having thus described my invention, what I claim as new therein and desire to secure 75 by Letters Patent is:—

1. A fluid driven tool of substantially the character described, comprising a compressing piston, a pressure driven piston and suitable housing for said pistons in which 80 the compressing piston compresses a charge of air and exerts retracting influence upon the pressure driven piston; said housing having a reservoir, a port between said reservoir and the part of the housing where the air is compressed; a second port between the reservoir and the space between the pistons by means of which two ports and said reservoir the charge of compressed air is conveyed into the space 90 between the pistons and permitted to there act expansively when retraction has taken place, an outlet valve leading to said reservoir from the front part of said housing and a similarly arranged valve close behind the 95 driven piston in its foremost position, said two valves adapted to permit escape of air in advance of the pistons on their forward strokes, and a port in the forward end of said housing adapted to admit air in front 100 of the pressure driven piston on its rearward stroke; and an air passage establishing communication from the compressing space of the compressing piston to said air admitting port in advance of the pressure 105 driven piston, whereby some of the air compressed by the compressing piston is utilized to drive the pressure driven piston rearward.

2. A fluid driven tool of substantially the 110 character described comprising a compressing piston, a pressure driven piston and suitable housing in which said pistons work, confining air in driving relation to the driven piston and providing by its rear portion a 115 compression chamber in which a charge of air is compressed by the compressing piston; said housing having a reservoir and ports connecting the interior of said housing with said reservoir and adapted respectively to 120 release air in advance of the pistons on their forward stroke, and to release a charge of compressed air from said reservoir to the space between the pistons when in their retracted position, and a replenishing valve 125 in said reservoir; said housing also having a port connecting said compression chamber with said reservoir and furthermore a by-

pass with a port at each end extending from the front end to the rear portion of the housing for supplying compressed air to the space in advance of the driven piston when 5 the compressing piston recedes.

3. A fluid driven tool of substantially the character described comprising a compressing piston, a pressure driven piston and suitable housing in which said pistons work, 10 confining air in driving relation to the driven piston and providing by its rear portion a compression chamber in which a charge of air is compressed by the compressing piston; said housing having a reservoir 15 and ports connecting the interior of said housing with said reservoirs and adapted respectively to release air in advance of the pistons on their forward stroke, and to release a charge of compressed air from said 20 reservoir to the space between the pistons when in their retracted position, and a replenishing valve in said reservoir; said housing also having a port connecting said compression chamber with said reservoir and 25 furthermore a by-pass with a port at each end extending from the front end to the rear portion of the housing, for supplying compressed air to the space in advance of the driven piston when the compressing piston 30 recedes, one of said by-pass ports being located in the compression chamber and adapted to be closed by said compressing piston after commencement of the compressing stroke, whereby retracting pressure is supplied during but a portion of the compression stroke.

4. A fluid driven tool of substantially the character described comprising a compressing piston, a pressure driven piston and 40 suitable housing in which said pistons work, confining air in driving relation to the driven piston and providing by its rear portion a compression chamber in which a charge of air is compressed by the compressing piston; said housing having a reservoir, ports connecting the interior of said housing with said reservoir and adapted to release air in advance of the pistons on their forward strokes, and other intercommunicating 45 ports adapted to supply air from said compressing chamber in advance of the driven piston when at its forward limit; one of said intercommunicating ports being controlled by the compressing piston and located in the compression chamber and adapted to be closed by the compressing piston after commencement of the compressing stroke, whereby retracting pressure is supplied during but a portion of compression 55 stroke and said last named port remaining closed until after the forward stroke of the driven piston, and trapping air in advance of the driven piston to cushion the latter; said housing also having a port releasing the

charge of compressed air from said reservoir to the space between the pistons when retracted, and also having a port in the compression chamber and in communication with said reservoir.

5. A fluid driven tool of substantially the character described, comprising a compressing piston, a pressure driven piston, and suitable housing for said pistons in which the compressing piston compresses a charge of air and exerts retracting influence upon the pressure driven piston; said housing having a reservoir, a port between said reservoir and the part of the housing where the air is compressed, a second port between the reservoir and the space between the pistons, by means of which two said ports and said reservoir the charge of compressed air is conveyed into the space between the pistons and permitted to there act expansively when retraction has taken place, an outlet valve leading to said reservoir from the front part of said housing and a similarly arranged valve close behind the driven piston in its forward position, said two valves adapted to permit escape of air in advance of the pistons on their forward strokes, and a port in the forward end of said housing adapted to admit air in front of the pressure driven piston on its rearward stroke; and an air passage establishing communication from the compressing space of the compressing piston to said air admitting port in advance of the pressure driven piston, whereby some of the air compressed by the compressing piston is utilized to drive the pressure driven piston rearward, said reservoir receiving air displaced on the forward stroke of the compressing piston, communication with the compression chamber and said reservoir being established when air is being supplied from said compression chamber to the space in front of the driven piston.

6. A fluid driven tool of substantially the character described, comprising a compressing piston, a pressure driven piston, and suitable housing for said pistons in which the compressing piston compresses a charge of air and exerts retracting influence upon the pressure driven piston; said housing having a reservoir, a port between said reservoir and the part of the housing where the air is compressed, a second port between the reservoir and the space between the pistons, by means of which two said ports and said reservoir the charge of compressed air is conveyed into the space between the pistons and permitted to there act expansively when retraction has taken place, an outlet valve leading to said reservoir from the front part of said housing and a similarly arranged valve close behind the driven piston in its forward position, said two valves adapted to permit escape of air in advance

of the pistons on their forward strokes, and a port in the forward end of said housing adapted to admit air in front of the pressure driven piston on its rearward stroke; said 5 second valve constituting a back-flow-checked passage communicating from the space which lies in rear of the driven piston after its forward stroke to the compression space of the compressing piston, whereby air 10 displaced from between the pistons, by the forward stroke of the compressing piston, is again delivered for compression.

7. A fluid driven tool of substantially the character described comprising a compressing piston, a pressure driven piston and suitable housing in which said pistons work, an air storage reservoir and a by pass, said reservoir and by-pass in coöperation with said housing and compressing piston confining 15 air in driving relation to both sides of the driven piston, said housing providing, by its rear portion, a compression chamber in which a charge of air is compressed by the compressing piston; said housing having 20 an escape port into said reservoir for the air displaced by the forward stroke of the compressing piston and a second port into said reservoir and a third port from said reservoir releasing the charge of compressed 25 air by means of said second and third ports and the reservoir to the space between the pistons when retracted; a check valve communicating 30 between the foremost end of said housing and said reservoir for displacing air into the reservoir by the forward stroke of said driven piston, said air storage reservoir having back-flow-checked communication 35 with said escape port, whereby air in the storage reservoir is subjected to compression.

8. A fluid driven tool of substantially the character described comprising a compressing piston, a pressure driven piston and suitable housing in which said pistons work, 45 an air storage reservoir and a by pass, said reservoir and by pass in coöperation with said housing and compressing piston confining air in driving relation to both sides of the driven piston, said housing providing, 50 by its rear portion, a compression chamber in which a charge of air is compressed by the compressing piston; said housing having an escape port into said reservoir for the air displaced by the forward stroke of the compressing piston and a second port into said reservoir 55 and a third port from said reservoir releasing the charge of compressed air by means of said second and third ports and said reservoir to the space between the pistons when retracted; a check valve communicating 60 between the foremost end of said housing and said reservoir for displacing air into the reservoir by the forward stroke of said driven piston said air storage reservoir having back-flow-checked communication

65 tion, through which it receives air displaced by the forward stroke of the compressing piston and having communication with the compression chamber through which its contained air is subjected to compression, and 70 also with the port that releases air to the space lying between the pistons when they are retracted.

9. A fluid driven tool of substantially the character described comprising a compressing piston, a pressure driven piston and a housing for said pistons, a reservoir and a plurality of ports connecting said housing and said reservoir, and a by pass with other ports therefor situated to connect the foremost portion of said housing with an inter-piston portion thereof, said reservoir and by-pass in coöperation with said housing, said ports and compressing piston constructed to confine air in driving relation to both sides 80 of the pressure driven piston and in compressing relation to the rear side of the compressing piston; said ports which admit air displaced by the forward strokes of both the pistons to the reservoir being back-flow- 85 checked and the remainder of said ports between the reservoir and the housing being open both ways.

10. A fluid driven tool comprising a compressing piston, a pressure driven piston, a suitable housing, a reservoir, a port between said reservoir and the part of the housing where the air is compressed; a second port between the reservoir and the space between the pistons by means of which two 100 ports and said reservoir the charge of compressed air is conveyed into confining air in driving relation to the rear of the driven piston and in compressing relation to the rear side of the compressing piston, a 105 port in the housing constructed to admit air at the forward end of the housing on the retraction of the driven piston and ports to permit escape of air on the forward strokes of the two pistons into said reservoir, 110 one of said escape ports being situated at the foremost end of said housing to displace air in front of the driven piston and a port to admit compressed air from said reservoir to the space between the pistons when retracted; said reservoir being provided with a passage in communication with the compression space of the housing, whereby air is not only stored under pressure, but is supplied to fill the space behind the compressing piston on the forward stroke of the latter.

11. A fluid driven tool comprising a cylinder, a tool piston working in said cylinder, a compressing piston working in said cylinder in retractive relation to the tool piston, a plurality of ports communicating with the cylinder, to wit, an air transmitting port at the front end; back-flow-checked air escape ports located respectively in front and 125 130

rear of the tool piston, when near the front end of the cylinder; a compressed air releasing port, at a point between the pistons when retracted; and a port at a point in the 5 rear end of the compression space; and there being a laterally disposed passageway communicating with all of said ports and a bypass with a port, connecting said air transmitting port with the space between the pis-

tons when said compressing piston is in its 10 rearmost position.

The foregoing specification signed at Syracuse New York, this 20th day of January, 1910.

JOHN L. WAGNER.
